FORGING HAMMER (FLUID OPERATED)

Howard Terhune, Cleveland, Ohio, assignor of one-half to The Champion Machine & Forging Company, Cleveland, Ohio, a corporation of Ohio

Application September 27, 1944, Serial No. 555,977

4 Claims. (Cl. 121—30)

1

This invention relates to improvements in forging hammers, and has to do primarily with the operating controls for a steam hammer. In hammers of this type, there are conventionally two valves, a control valve for so directing the live steam and the exhaust as to drive the ram up or down, and a throttle valve for determining the rate of flow of steam to the steam chest surrounding the control valve. Conventionally the throttle valve is operator actuated exclusively, while the control valve is partially operator actuated and partially automatic.

In the conventional construction the throttle is open wide for the down stroke of the ram and open to a very slight degree only for the up stroke, inasmuch as a very slight flow of steam is required for holding the ram at the top of its stroke or causing it to "swing" up and down near the top of its stroke. This conventional arrangement is open to certain objections. For example, the ram with its upper die may rebound sharply at times after a blow has been struck, and although the control valve is disposed to admit steam under the piston as soon as the treadle is released by the operator the approximately closed throttle may not admit enough steam to hold the piston up after rebound and it may fall with the result of damaging a forging then being removed by the operator or of injuring the operator.

In accordance with my invention the throttle is automatically maintained at least one quarter open at the beginning of the up stroke, so that sufficient steam is admitted to the cylinder below the piston to prevent any possible dropping of the ram, and the throttle is gradually moved toward closed position as the ram travels upwardly, its final opening being comparable to the constant opening on the upstroke in such machines as heretofore constituted.

One of the objects of the invention therefore is the provision of means for causing quick return of the ram to idle position after a blow has been struck.

Another object is the provision of means for preventing accidental repeat blows.

Other objects and features of novelty will appear as I proceed with the description of that embodiment of the invention which, for the purposes of the present application, I have illustrated in the accompanying drawings, in which

Fig. 1 is a front elevational view of a steam hammer embodying the invention;

Fig. 2 is a side view of the same;

Fig. 3 is a fragmental view showing the position of the valve parts at the instant the op-

2

erator's treadle is depressed and the ram starts on its down stroke;

Fig. 4 is a similar view with the ram at the end of its down stroke and the operator's treadle still depressed;

Fig. 5 is a similar view with the ram down immediately following the release of the treadle by the operator;

Fig. 6 is a similar view with the treadle released and the ram "swinging" or idling in the upper part of its path of travel, and

Fig. 7 is a detail sectional view, on a larger scale, of a modified form of throttle valve.

In the drawings the base of a steam hammer is illustrated at 10, with frame standards 11 secured thereto. 12 is a tie plate member carrying a cylinder unit 13 in the cylinder 13' of which is slidably disposed a piston 14 at the top of a piston rod 15. At the lower end of the latter there is mounted a ram 16 which travels between guides 17 on the standards 11 and carries the moving die 18. A lower die 19 is mounted in an anvil 19 supported in base 10.

The control valve and the throttle valve are both formed in or carried by the cylinder unit 13, as is usual in machines of this kind. The control valve comprises a ported sleeve 20 set into a cylindrical hole in the cylinder unit. The lower end of this hole communicates with an exhaust pipe 21. A hollow spool valve 22 slides up and down in sleeve 20, its end spiders being attached to a rod 23 slidably guided in a cover 24, and connected at its upper end to a link 25 which is pivotally mounted in the outer or free end of an arm 26 that swings about a pivot 27 carried by the cylinder unit. A passage 28 connects ports 29 in sleeve 20 with the upper end of cylinder 13' and a passage 30 connects ports 31 in the sleeve with the lower end of the cylinder. A steam chest 32 surrounding the sleeve 20 communicates with the interior of the control valve through ports 33.

The throttle valve comprises a sleeve 35 set into a cylindrical hole in the outer structure of the cylinder unit. This sleeve has a port 36 in communication with steam chest 32 and a port 37 in communication with a conductor 38 for incoming steam. An oscillatable valve piece 39 within sleeve 35 is movable to control the amount of opening of port 36 and thereby the flow of steam into the chest 32.

On the base of the machine there is mounted the usual treadle, comprising a rock shaft 40 and foot piece 41. From one end of shaft 40 a crank arm 42 extends forward to a pivotal

connection with an upwardly extending link 43 which is pivotally connected at its upper end with an arm 44 mounted to swing about a pivot 45 carried by one of the frame standards. Another link 46 pivotally connected with arm 44, and containing any suitable means for adjusting its length, extends upwardly to a pivotal connection with a lever 47 that is fulcrumed upon a pin 48 carried by one of the frame standards 11. Upon the opposite end of lever 47 there is mounted a pivot pin 49 upon which is oscillatably supported the hub of a rock lever 50 having two short arms 51 and 52 and a long downwardly extending cam arm 53 of familiar form. The latter cooperates with an inclined cam surface 54 on the ram 16. The arm 51 of the rock lever is connected by means of a rod 55 with a free end of arm 26, to which is also attached the link 25 previously mentioned. The arm 52 of rock lever 50 is connected by a rod 56 with a crank arm 57 which is operatively fixed to one end of a shaft 58 that carries valve piece 39 of the throttle valve. The effective length of arm 57 may be adjusted by moving its pivotal connection with rod 56, into any one of a series of longitudinally spaced holes, as indicated in Fig. 1. The angular relation of arm 57 with respect to valve piece 39 may also be adjusted by means of a pin and slot connection 59 between the arm 57 and an arm 60 attached to shaft 58.

In Fig. 7 I have illustrated a modified form of throttle valve, by means of which the angular adjustment of the valve relative to port 36 of sleeve 35 may be somewhat more conveniently accomplished. In this case the movable valve element operated by rod 56 is a sleeve 65 having at least two ports 66 and 67. The maximum opening of inlet port 36, 66 is controlled by an inner sleeve 68 which remains fixed under normal conditions. In case it is desired to change the effective opening of the intake port for a given position of the operating sleeve 65, the inner sleeve 68 is rotatably adjusted. This may be accomplished by attaching a shaft to sleeve 68 and causing it to project rearwardly through the valve housing in much the same way that the shaft 58 projects forwardly. Such a rear shaft may have a crank arm connected to a link extending downwardly to any point conveniently within the reach of the operator, such connections being omitted from the drawing for the sake of clearness and simplicity.

Operation.—Assuming that the ram 16 is in its upper or idle position and that the operator desires to have the hammer strike a blow, he then depresses the foot treadle to turn lever 47 to the position illustrated in Fig. 3. This results in lifting the pivot 49 and with it both of the rods 55 and 56. The upward movement of rod 55 raises control valve 22 to the position shown in Fig. 3 and the upward movement of rod 56 swings throttle valve 39 to a partially open position as also shown in that figure. Steam or other pressure fluid then flows from pipe 38 through port 37 into sleeve 35, out of that sleeve through port 36 into annular steam chest 32, through ports 33 into sleeve 20 and out through ports 29 and passage 28 into the upper end of cylinder 13'. The piston 14 then travels rapidly downward together with piston rod 15 and ram 16. As the ram descends the cam surface 54 permits cam arm 53 to turn clockwise through a small angle, pulling down on rod 55 and pushing up rod 56. The upward movement of rod 56 turns valve piece 39 clockwise, thereby opening port 36 further. The hammer

is thus caused to strike a heavy blow. By the time the ram has reached the bottom of its stroke, rod 55 will have pulled valve 22 downward and the two valves will occupy the positions illustrated in Fig. 4.

Now when the blow has been struck the operator naturally releases treadle 40, 41 and the lever 47, which is biased upwardly by spring means not shown, moves to the position of Fig. 5. This causes pivot 49 to descend and with it rods 55 and 56. Spool valve 22 is thereby lowered so as to direct live fluid into the cylinder beneath the piston 14 and to enable fluid above the piston to exhaust through passage 28, ports 29, and through hollow valve 22 to exhaust pipe 21. At the same time throttle valve 39 is closed to some extent. The adjustments are such however that port 36 remains at least one quarter open; consequently the rise of the piston and the ram is rapid at the start of the up stroke. As the ram rises however, the cam arm 53 swings counterclockwise, drawing the rod 56 down and causing valve 39 to almost close port 36. Before this occurs however, sufficient steam has been admitted to the cylinder below the piston and to the steam chest 32 to insure fully against any accidental dropping of the ram. As the ram approaches its uppermost position and the arm 53 swings counterclockwise the spool valve 22 is raised to the position of Fig. 6, where port 29 is slightly open to steam within the steam chest while exhaust from the cylinder below the piston is also slightly open. This causes travel of the piston and ram downwardly to approximately the broken line position of Fig. 6, the rocking of the rock lever 50 clockwise about its pivot 49 pulls the spool valve 22 down just far enough to reverse the direction of flow of live steam and exhaust so that the piston and ram again travel upwardly. This is the idling motion which is often referred to in the industry as "swinging." During this swinging of the ram the throttle, because of the short reciprocations of rod 56, is open slightly less at the top of the ram stroke than at the intermediate positions indicated by broken lines in Fig. 6, but during the swinging action the throttle opening is always relatively small, as it should be in order to conserve steam.

It will be apparent therefore that by the use of my invention the ram is caused to rise rapidly after striking a blow and to be supported in idle position with sufficient steam to preclude any possibility of accidental movement down to the vicinity of the anvil, but that the throttle is automatically actuated toward closed position as the ram rises, which permits a very small flow of steam at the top of the ram stroke.

Having thus described my invention, I claim:

1. In a fluid operated hammer, a ram, a throttle valve, a control valve, operator actuated means for moving said throttle and control valves to drive the ram up and down, and automatic means responsive to ram movement for causing the throttle valve to move on the up stroke of the ram from a relatively open position to a relatively closed position.

2. In a fluid operated hammer, a ram, a throttle valve, a control valve, operator actuated means tending to open said throttle valve for the down stroke of the ram and to close it for the up stroke, and automatic means responsive to ram movement for modifying the action of the throttle valve to provide relatively wide opening at the

start of the up stroke and gradually decreased opening as the ram moves upwardly.

3. In a fluid operated hammer, a ram, a piston connected therewith, a cylinder for said piston, a throttle valve, a control valve, operator actuated means tending to open said throttle valve for the down stroke of the ram and to close it for the up stroke, and means responsive to the down stroke of the ram for moving the throttle toward open position and the control valve toward the position for feeding live fluid to the cylinder above the piston and responsive to the up stroke of the ram for moving the throttle toward closed position and the control valve toward the position for feeding live fluid to the cylinder below the piston. 10

4. In a fluid operated hammer, a ram, a throttle valve, a control valve, a rock lever, a pivot therefor, operator actuated means for moving said

5 pivot up or down, means for rocking said rock lever in response to ram travel, and operative connections between said rock lever and said throttle valve and between said rock lever and said control valve, whereby both valves are shifted when the pivot point moves up or down, and whereby both valves are moved to a lesser extent as the ram moves up or down.

HOWARD TERHUNE.
